STAND FOR FIREPLACE TOOLS

Harold S. Hobson, Jr., Seymour, Ind., assignor to Seymour Manufacturing Co., Seymour, Ind., a corporation of Delaware

Filed Aug. 17, 1964, Ser. No. 81,320

Term of patent 14 years

(Cl. D33—17)

FIG. 1 is a perspective view of my new design of a stand for fireplace tools;

FIG. 2 is a front elevational view of the stand;

FIG. 3 is a side elevational view thereof;

FIG. 4 is a top plan view thereof, and

FIG. 5 is a detailed cross-sectional view taken on line 5—5 of FIG. 2.

I claim:

The ornamental design for a stand for fireplace tools, substantially as shown.
